UNITED STATES PATENT OFFICE.

JAY G. HOBSON, OF MARTINSVILLE, INDIANA.

METAL-GRINDING MACHINE.

1,320,859.

Specification of Letters Patent.

Patented Nov. 4, 1919.

Application filed April 11, 1919. Serial No. 289,217.

To all whom it may concern:

Be it known that I, JAY G. HOBSON, a citizen of the United States, and a resident of Martinsville, in the county of Morgan 5 and State of Indiana, have invented new and useful Improvements in Metal-Grinding Machines, of which the following is a specification.

This invention relates to metal grinding 10 machines and has particular reference to that class of machines employed as a means for sharpening or repointing phonograph needles.

An important object of the invention is to 15 provide in a device of the above mentioned character a means whereby a plurality of needles may be sharpened or repointed simultaneously.

A further object of the invention is to 20 provide in a device of the above mentioned character a means whereby the needles are rotated about their axis and moved in a circular path during the sharpening or repointing operation.

25 A further object of the invention is to provide in a device of the above mentioned character a means whereby the needles may be inserted into the machine so that their points will lie in a common horizontal plane 30 to effect a uniform and even grinding upon the ends thereof.

35 A further object of the invention is to provide in a device of the above mentioned character a means whereby the abrasive material may be moved into contact with the points of the needles and retained in contact therewith during the sharpening or repointing operation.

40 A further object of the invention is to provide a device of the above mentioned character which is simple in construction, compact, durable and reliable in operation.

45 Other objects and advantages of the invention will be apparent during the course 50 of the following description taken in connection with the accompanying drawings.

In the drawings, forming a part of this specification and in which like parts are employed to designate like parts throughout 55 the same,

Figure 1 is a top plan view of the device embodying my invention,

Fig. 2 is a vertical sectional view taken on line 2—2 of Fig. 1,

55 Fig. 3 is a fragmental sectional view simi-

lar to that shown in Fig. 2, the abrasive material being shown in a lowered position,

Fig. 4 is a detailed horizontal sectional view taken on line 4—4 of Fig. 3, and,

Fig. 5 is a top plan view of a needle carrying element.

In the drawings, wherein for the purpose of illustration is shown a preferred form of my invention, the numeral 5 indicates a base having a housing 6, the base 65 together with the housing 6 forming a container within which the several coöperating elements hereinafter described are arranged. To the base 5 there is centrally secured a vertically disposed post 7, the post being 70 square in cross section and secured in position by means of a screw or the like as shown at 8.

Within the lower portion of the post 7 there is journaled a horizontally disposed 75 shaft 9. The shaft 9 is further journaled within the housing 6 as shown at 10 and is prevented from moving longitudinally by means of pins passed transversely through the shaft as shown at 11. The shaft 9 is 80 bent at one end to form a substantially L-shaped portion as shown at 12 and is provided at its other end with an operating lever 13. The shaft 9 is bent substantially intermediate its ends to provide a U-shaped 85 portion 14. Upon the square post 7 there is slidably mounted a disk 15 adapted to be raised and lowered through the instrumentality of the operating lever 13 as will hereinafter be more fully described. The disk 90 15 is prevented from rotating, due to the fact that the central opening thereof is square and is only sufficiently larger than the square post 7 to permit free vertical movement of the disk 15. The disk 15 is 95 provided at its periphery with an angularly disposed dependent flange 16 having its outer face provided with suitable abrasive material or coating as shown at 17.

The post 7 at its upper end is reduced to 100 provide a stub shaft 17 upon which is journaled a relatively large gear 18 having peripheral flanges 19 between which the gear teeth 20 are disposed. The gear 18 is retained in position upon the shaft 17 by 105 means of a nut 21 having screw-threaded engagement with the shaft 17 as shown at 22. As a means for rotating the gear 18 there is provided a vertically disposed handle 23 which is secured to the gear 8 an ap- 110

preciable distance from the axis of the shaft 17.

The housing 6 at its upper inner edge is depressed or cut away as shown at 24 to provide an internal gear 25 which meshes with a plurality of pinions 26. The pinions 26 are spaced an appreciable distance from each other and mesh with the teeth 20 of the gear 18. It is apparent from the structure thus far described that by rotating the gear 18 the pinions 26 are not only rotated about their known axis but are moved in a circular path about the axis of the shaft 17. Upon the housing 6 there is disposed an annular ring 27 which is retained in position by means of screws or the like as shown at 28. The ring 27 and the flanges 19, as is apparent, serves as a means for retaining the pinions 26 in their respective positions as shown in Fig. 2. The pinions 26 are provided centrally with preferably rubber hubs 29 having openings 30 therein, which openings are adapted to receive the phonograph needles 31 which are desired to be sharpened or repointed.

In order to limit the downward movement of the needles 31 when being inserted so that the points of the needles will all lie in a common horizontal plane I provide a reciprocating plunger 32, square in cross section to prevent turning within the housing 6. The plunger 32 is provided with a head 33 adapted to receive thereupon the points of the needles 31 when being inserted. The plunger 32 is provided at its outer end with a push button 34. Between the push button and the housing 6 there is disposed a suitable coil spring 35 which is adapted to normally retain the plunger 32 in a retracted position as clearly shown in Fig. 2.

In use, the device as a whole may be conveniently located to the phonograph and as the needles are used and consequently dulled they are inserted into the openings 30 of the hubs 29. Each time that a needle is inserted the plunger 32 is moved to the position shown in Fig. 3 so that when the machine is filled to its capacity all of the points of the needles will lie in a common horizontal plane to insure even and uniform grinding thereof. It is to be understood that the needles are inserted in the desired hub when that hub is directly above the head 33. The selected hub may be brought into registration with the head 33 by simply rotating the gear 18 as is apparent. When a desired number of needles have been placed in the machine, it need not be filled to its capacity however, the lever 13 is moved to partially rotate the shaft 9 whereupon the disk 15 is moved upwardly due to the engagement of the bent portions 12 and 14 therewith. The gear 18 is then rotated by means of the handle 23 whereupon the needles 31 having their pointed ends engaging the abrasive ma-

terial or coating 17' are rotated about their axis and moved bodily in a circular path about the axis of the stub shaft 17. By retaining the engagement between the pointed ends of the needles 31 and the abrasive material or coating 17' and continuing to rotate the gear 18, a uniform sharpening or repointing of the needles 31 may be effected. When the needles have been sufficiently sharpened or sufficiently repointed, rotation of the gear 18 is discontinued and the disk 15 is lowered to its normal position whereupon the needles 31 may be easily withdrawn from the openings 30 of the hubs 29. It is to be understood that the plunger 32 is to be allowed to retain its normal position as shown in Fig. 2 under the influence of the spring 35 at all times other than when the needles are being inserted as hereinbefore described. Because of the peculiar construction and location of the plunger and head 33 there is no interference set up to hinder the sharpening or repointing operation when the plunger is allowed to remain in its normal position under the influence of the spring 35 as clearly shown in Fig. 2.

It is to be understood that the form of my invention herewith shown and described is to be taken as a preferred example of the same, and that various changes in the shape, size and arrangement of parts may be resorted to without departing from the spirit of the invention or the scope of the subjoined claims.

Having thus described my invention, what I claim as new and desire to secure and protect by Letters Patent of the United States, is:

1. A phonograph needle sharpener comprising an external gear and an internal gear, a plurality of pinions engaging said gears, means for rotating the external gear to rotate said pinions about their axis and move them in a circular path, means for retaining the phonograph needles centrally within said pinions, and abrasive material for engaging the points of the needles during their rotation.

2. A phonograph needle sharpener comprising an external gear and an internal gear, a plurality of pinions engaging said gears, means for rotating the external gear to rotate said pinions about their axis and move them in a circular path, means for retaining the phonograph needles centrally within said pinions, abrasive material for engaging the points of the needles during their rotation, and means for moving the abrasive material into and out of engagement with the points of the needles.

3. A phonograph needle sharpener comprising an external gear and an internal gear, a plurality of pinions engaging said gears, means for rotating the external gear to rotate said pinions about their axis and

- move them in a circular path, means for retaining the phonograph needles centrally within said pinions, abrasive material for engaging the points of the needles during 5 their rotation, means for moving the abrasive material into and out of engagement with the points of the needles, and means for bringing the points of the needles into a common plane.
- 10 4. A phonograph needle sharpener comprising an external gear and an internal gear, a plurality of pinions spaced from each other and having engagement with said gears, means for rotating the external gear 15 whereby said pinions are rotated about their axis and moved in a circular path, means for retaining the phonograph needles centrally within said pinions, a reciprocating disk, abrasive material secured to said disk, and 20 means for reciprocating said disk whereby the abrasive material is moved into and out of engagement with the points of the needles.
5. A phonograph needle sharpener comprising a pinion, means for retaining a phonograph needle centrally within said pinion, an abrasive material for engaging the point 25 of the needle, and means for rotating said pinion about its axis and for simultane-
- ously moving said pinion bodily in a given path during the engagement of said abrasive material with the point of said needle.
6. A phonograph needle sharpener comprising a pair of gears, a pinion disposed between and engaging said gears, means for moving one of said gears to rotate said pinion about its axis and move said pinion bodily in a given path, means for retaining a phonograph needle centrally within said pinion, and abrasive material for engaging the point of the needle when the pinion is 35 rotated and moved bodily.
7. A phonograph needle sharpener comprising a stationary element, a movable element, a pinion interposed between said stationary and movable elements, said pinion 40 having engagement with said stationary and movable elements, means for moving the movable element to rotate said pinion about its axis and move said pinion bodily in a given path, means for retaining a phonograph needle centrally within said pinion, and abrasive material for engaging the point 45 of the needle during its rotative and bodily movement.

JAY G. HOBSON.
